Primary Examiner — Jonathan J Han*Assistant Examiner* — Christen Pilar Brown(74) *Attorney, Agent, or Firm* — Marshall A. Lerner; Steven J. Kim; KLEINBERG & LERNER, LLP(57) **CLAIM**

The ornamental design for a shoe midsole periphery, as shown and described.

DESCRIPTION

FIG. 1 is a front perspective view of an embodiment of a shoe midsole periphery thereof; and, FIG. 2 is a left side view thereof.

Broken lines shown in the drawings represent portions of the shoe and form no part of the claimed design.
